UNITED STATES PATENT OFFICE

2,144,729

APPARATUS FOR FORMING TYING STRIPS
AND APPLYING THE SAME TO BAGSAdolph Potdevin, Garden City, N. Y., assignor to
Potdevin Machine Company, Brooklyn, N. Y., a
corporation of New YorkOriginal application May 3, 1937, Serial No.
140,436. Divided and this application March 9,
1938, Serial No. 194,813

11 Claims. (Cl. 271—1)

This invention relates to improvements in machines for making bags and is particularly directed to an improved device for applying a metal tie strip to the end of bags of the type known commercially as metal tie bags.

This application is a division of my copending application Serial No. 140,436, filed May 3, 1937, and is directed more specifically to a device of the character indicated having novel feeding means for the blanks in the making of such bags as above referred to.

In making metal tie bags a small strip of metal extending transversely of the bag is applied to the open end of the bag and when the bag is to be closed the strip and bag end are rolled over upon the bag several times and the projecting ends of the tie strip are bent over the bag body to hold the bag closed.

It is an object of the present invention to provide a machine which is full automatic in its operation and is adapted to form the tie strips and to apply the same to the bag in continuous operation. However, the present application is more specifically directed to the novel means for withdrawing bags from the bottom of a stack of bags and means for moving the bags laterally toward the discharge end of the machine.

In the accompanying drawings I have illustrated the machine of the present invention.

30 In the drawings:

Fig. 1 is a plan view of the machine;

Fig. 2 is a view showing the charging end of the machine in elevation;

35 Fig. 3 is a part sectional elevational view of the cam mechanism by which the bags to which the tie strips are to be applied are fed forward into the machine;

Fig. 4 is a view of the same part of the machine but with the parts in a different position; and

Fig. 5 is a section on line 5—5 of Fig. 2.

Referring to the drawings in detail: 2 designates the bags to which tie strips are to be applied. The bags are taken from a magazine 4 located at the charging end of the machine and passed through the machine continuously while traveling laterally. During the advance of the bags a metal strip 6 enclosed in paper tape 8 and constituting the tie strip is applied to the projecting flap 10 which is provided for this purpose at the open end of each bag.

The metal tape 6 and the paper tape 8 are taken from supply spools 12 and 14, respectively,

the paper tape being folded about the metal strip as the two progress through the machine.

The supply bags 2 are stacked at the magazine 4 on a table or bed 16. The bags in the stack lie transversely of the machine and are fed forward lengthwise successively from the bottom of the stack with the bag bottom in the lead, into position to be picked up by the forwarding mechanism which forwards the bags laterally toward the discharge end of the machine.

The magazine table or bed is provided with adjustable corners 17, the corners 17 at the bottom end of the bags being provided with lugs for supporting this end of the bags. With a stack of bags disposed on this table the flap 20 of the lowermost bag of the stack will sag downwardly through the opening 18 in the table, as seen in Figs. 2 and 3.

Beneath the magazine table or bed 16 is a pair of forwarding jaws, designated 22 and 24. The jaw 22 is affixed to an arm 26, the jaw and arm being pivoted on a stud 28. The jaw 24 is affixed to arm 30 also pivoted on the stud 28 which is carried on the free end of a lever 32 pivoted intermediate its ends on shaft 34.

The free end of the arm 26 carrying the jaw 22 is provided with a cam follower 36, the free end of the arm 30 for the jaw 24 with a cam follower 38 and the free end of lever 32 with a cam follower 40. The cam follower 36 cooperates with a cam 42 and the cam follower 38 cooperates with a cam 44. Both of these cams are mounted on the shaft 34. The cam follower 40 cooperates with cam 46 on a shaft 48.

The operation of the jaws 22 and 24 and the various cams controlling the same will be described in detail hereinafter, but at this point I would like to say that this mechanism is so arranged that at the proper time the jaws 22 and 24 will close upon the flap 20 at the bottom end of the lowermost bag in the stack of bags and move the bag forward sufficiently to be picked up by the rollers 50 which are mounted to rotate about axes extending lengthwise of the machine. The arm 32 has four motions. First it moves forward with the jaws 22 and 24 open to grip the bag. It then moves away from the feed rollers 50 pulling the bottom end of the gripped bag off its support. The arm then moves forward carrying the bag to the feed rollers, the jaws open and the assembly returns to starting position.

The forwarding rollers 50 forward each bag crosswise of the machine toward a table or bed 52. This table 52 is provided with a side plate 55

56 and an end plate 58 for promoting proper positioning of the bags. These plates are adjustable so as to accommodate the machine to bags of different lengths as well as to bags of different widths.

5 As each bag is being fed forward toward the table or bed 52 plate 60 which is being reciprocated transversely to the bag motion is returning under plate 56, and when the plate 60 has moved 10 under 56 the bag drops to table 52 to be pushed by the downwardly bent flange 62 on the plate 60 to forwarding rollers 66. The rollers 66 deliver the bags between upper and lower forwarding chains designated 68 and 70, respectively.

15 Reverting to the pusher mechanism by which the bags are pushed from the table 52 it will be seen that webs 72 are secured to the underside of the pusher plate 60. These webs are carried by a plate 74 mounted on rails 76 extending lengthwise of the machine. Secured to the plate 74 is a short link 78 pivoted to the plate at 80, this link being pivotally attached to a lever 82 carried by shaft 84. The shaft 84 also carries crank arm 86 pivotally connected to connecting rod 88, the free end of which is attached to crank disc 90. The connection of the connecting rod 88 to the crank arm 86 is adjustable so that the throw of the arm or lever 82 and hence throw of the pusher 60 may be adjusted to accommodate bags of different widths.

30 The driving motor for the machine is designated 94. This motor, through a sprocket and chain drive, drives a pinion 96 meshing with a spur gear 98 mounted on a stub shaft which carries a gear 100. The gear 100 meshes with gear 102 mounted on shaft 104 carrying pinion 106, the latter meshing with a pinion 108 in mesh with a pinion 110 on shaft 112. The latter extends longitudinally of the machine toward the 40 charging end thereof where the shaft terminates. This end of the shaft carries a gear 113 meshing with wide faced gear 114, the gear 114 meshing with a gear 116 on the shaft 34 carrying the cams 42 and 44. The opposite end of this cam shaft 34 carries a gear 118 meshing with gear 120 in mesh with gear 122 on the shaft carrying the lower roller of the two forwarding rollers 50, this shaft carrying a gear 126 in mesh with gear 128 on the shaft of the upper rollers of the forwarding rollers 50.

50 This provides a drive for the forwarding rollers 50 and for the cams 42 and 44.

Below the cam shaft 34 is the cam shaft 48 carrying the cam 46 and this shaft is also driven off the gear 118 through gear 130. The shaft 48 carries bevel gear 132 meshing with bevel gear 134 on the shaft 136 carrying the crank 90.

60 It is to be noted that the grippers 22 and 24, their controlling cams, the forwarding rollers 50, and the gear trains for driving the cams and forwarding rollers, as well as the crank for driving the pusher 60 can be adjusted transversely of the machine by hand wheel 131.

65 The drive for the forwarding chains 68 and 70 is from a pinion 138 on the stub shaft 104, gears 140, 142, 144, bevel gears 146 and 148 which drives shaft 150 carrying the sprocket for the lower chain 70. This shaft 150 carries gear 152 meshing with gear 154 on the shaft 156 carrying the 70 upper chain 68. This gear train will drive the lower lead of the chain 68 and the upper lead of the chain 70 in the same direction toward the delivery end of the machine.

75 The bags are gripped between the upper lead of the lower chain 70 and the lower lead of the

upper chain 68 as more fully shown and described in my copending application Serial No. 140,436. This provides for gripping the bags so as in effect to attach the bags successively to the forwarding chains for advancement.

5 As above stated the metal tape 6 forming part of the tie strip is taken from the supply reel 12. This reel lies beneath the machine and the tape is drawn upwardly to the machine bed and then forward toward the discharge end of the machine 10 by feed rolls 166. The roll 12 is equipped with suitable retarding mechanism 170 to prevent overrunning. The metal tape as it is drawn upwardly passes about guide rolls 172, 174, 176, 178, 180, 181, 182 and roller 184 which is carried 15 on the same shaft 186 as the idler sprockets 188 on the lower chain 70.

The paper tape 8 which is taken from the reel 14 and which is to enclose the metal tape 6 before the latter is placed in position on the bags 20 2 is also forwarded by the feed rollers 166.

This tape passes from the reel 14 about guiding and tensioning rollers (not shown), then between roller 192 and gluing roller 193 where three stripes of adhesive are continuously applied to 25 the face of the tape as more fully shown and described in my copending application Serial No. 140,436.

The paper next passes about the rollers 180, 181 and 182, previously referred to. The roller 30 182 is so shaped that as the paper tape passes the same one edge of the tape will be turned inwardly over and upon the metal tape 6 to bring one of the adhesive stripes into engagement with the face of the metal tape. As the paper tape 35 and metal tape continue their forward movement another stripe of adhesive 198 is applied to the turned-over part of the tape.

The paper tape then passes over the roller 184 and the two tapes from thence travel lengthwise 40 of the machine beneath the projecting flap 10 of the bags 2, the adhesive stripe 198 contacting the underside of the flap.

As the paper and metal tapes together with the bags travel lengthwise of the machine they pass 45 a plate 204 which deflects that portion of the paper tape carrying the adhesive stripe 194 over upon the upper face of the flap 10 of the bags. The tapes and bags then pass beneath a hinged plate 208, to the pair of feed rollers 166 which 50 press the tapes and bags together.

The tie strip is continuous, as will be understood, and after it has passed the rollers 166 it is cut off between adjacent bags 2 by a cutter bar 214. After the tie strip has been severed the 55 chains 68 and 70 continue the lateral advance of each bag with tie strip attached until the same is picked up by discharge rollers 216 by which the bags are successively discharged into a receiving trough 218. The discharge rollers 216 60 are geared together and are driven off the gear 154.

The feed roller 166 and its cooperating roller are driven off the gear 152 through intermediate gear 153 and gears 155. 65

The shaft which carries the sprocket for one end of the lower forwarding chain 70 is provided with a gear meshing with a pinion which in turn meshes with another pinion on the shaft of the lower pair of forwarding rollers 66, and is 70 suitably geared to the shaft of the upper pair of forwarding rollers 66, as fully shown and described in my copending application Serial No. 140,436.

The drive for the adhesive-applying roller 193, 75

which constitutes no part of the invention of the present application, is also fully described and illustrated in my copending application Serial No. 140,436 of which the present application is a division.

For purposes of threading the machine initially the roller 182 which cooperates with the adhesive-applying disc 193 is mounted on a pivoted arm 240 to which is attached an arm 242. This arm is 10 provided with a notch 244 adapted to engage the shaft 246 which mounts the roller 182. By lifting up the roller 182 and engaging the notch 244 with the shaft 246 the roller 182 will be held out of 15 cooperative relation with the adhesive-applying disc 193.

It will be seen from all of the foregoing that the present invention provides an automatic machine so constructed and arranged that bags are continuously taken from a supply stack and forwarded laterally through the machine. At the same time paper tape and metal tape are continuously fed lengthwise through the machine in superimposed relation to each other, adhesive being applied to the paper before the same contacts 25 the metal strip and the paper being wrapped about the metal, these two tapes finally being brought into superimposed relation with respect to the laterally traveling bags, whereupon the paper tape is folded over and attached to the bags. 30 Prior to the discharge of the bags from the machine the tapes, which constitute the tying strip, are severed between adjacent bags so that in the finished bag we find a tying strip made up of paper and metal attached to the projecting flap 35 on the open end of the bag with the ends of the tying strip projecting a short distance beyond the sides of the bag.

It is to be understood that the details of construction and arrangement of parts herein shown 40 and described may be varied without departing from the spirit and scope of my invention.

What I claim is:—

1. A machine of the class described comprising in combination, means for successively withdrawing 45 bags from the bottom of a stack of bags, a reciprocating pusher adapted to engage the side of each withdrawn bag and to move the same laterally, forwarding rollers receiving the bags from said pusher, and a pair of superimposed chains receiving the bags from said rollers to be gripped therebetween thereby to continue the lateral movement of the bags toward the discharge end of the machine.

2. A machine of the class described comprising 55 in combination, cam-controlled grippers for automatically gripping the bottomed end of the lower bag of a stack of bags, a pair of forwarding rollers, a cam for pivoting said grippers to effect delivery of the gripped bag to said rollers, a reciprocating 60 pusher for engaging each bag as it is released by the said forwarding rollers, a second pair of forwarding rollers for receiving each bag from the pusher, and forwarding chains for continuing the advance of the bags to the discharge end of the machine.

3. A machine of the class described comprising 65 a pair of grippers for automatically withdrawing successively the lowermost bag from a bag stack, a pivot for the jaws of said grippers, a cam for pivoting each gripper jaw, a pivoted arm carrying said grippers, and a cam for bodily pivoting the grippers, whereby the grippers are caused to move into and out of operative position with respect to the bag stack.

4. A machine of the class described comprising

in combination, a bag magazine, means for successively withdrawing bags from the bottom of the magazine, a receiving table or bed, forwarding rollers for receiving the withdrawn bags and depositing them upon said table or bed, a pusher 5 for pushing the bags from said table, cams controlling said grippers, driving mechanism for said cams, rollers and pusher, and means for adjusting said grippers, rollers, cams and driving mechanism relatively to the bag magazine to accommodate the machine to different length bags.

5. A machine of the class described comprising in combination, cam-actuated means for successively and automatically withdrawing bags from the bottom of a stack of bags, a reciprocating 15 pusher adapted to engage the side of each withdrawn bag and to move the same laterally, forwarding rollers receiving the bags from said pusher, and a pair of superimposed chains receiving the bags from said rollers to be gripped 20 therebetween thereby to continue the lateral movement of the bags toward the discharge end of the machine.

6. A machine of the class described comprising in combination, a bag magazine, cam-controlled 25 grippers for automatically gripping the bottomed end of the lower bag in said magazine, a cam for pivoting said grippers to effect withdrawal of the gripped bag from the stack, forwarding rollers, a reciprocating pusher for actuating each bag, as 30 it is released by the grippers, to said forwarding rollers, and superimposed forwarding chains for continuing the advance of the bags to the discharge end of the machine.

7. A machine of the class described comprising 35 in combination a bag magazine, a pair of grippers for automatically withdrawing successively the lowermost bag from said magazine, a pivot for the jaws of said grippers, a cam for pivoting each gripper jaw, a pivoted arm carrying said grippers, 40 and a cam for bodily pivoting the grippers, whereby the grippers are caused to move into and out of operative position with respect to the bag stack, a receiving table or bed, forwarding rollers for receiving the withdrawn bags and 45 depositing them upon said table or bed, a pusher for pushing the bags from said table, cams controlling said grippers, driving mechanism for said cams, rollers and pusher, and means for adjusting said grippers, rollers, cams and driving mechanism relatively to the bag magazine to accommodate the machine to different length bags.

8. A machine of the class described comprising in combination, means for successively withdrawing bags lengthwise from the bottom of 55 a stack of bags, a reciprocating pusher adapted to engage the side of each withdrawn bag and to move the same laterally, forwarding rollers receiving the bags from said pusher, and a pair of superimposed chains receiving the bags from 60 said rollers to be gripped therebetween thereby to continue the lateral movement of the bags toward the discharge end of the machine.

9. A machine of the class described comprising 65 in combination, cam-controlled grippers for automatically and successively gripping the flap on the bottomed end of the lower bag of a stack of bags, a cam for pivoting said grippers to effect withdrawal of the gripped bag lengthwise from 70 the stack, a reciprocating pusher for actuating each bag, as it is released by the grippers, to forwarding rollers, and forwarding chains for continuing the advance of the bags to the discharge end of the machine.

10. A machine of the class described comprising a pair of grippers for automatically withdrawing successively and lengthwise the lowermost bag from a bag stack, a pivot for the jaws of said grippers, a cam for pivoting each gripper jaw, a pivoted arm carrying said grippers, and a cam for bodily pivoting the grippers, whereby the grippers are caused to move into and out of operative position with respect to the bag stack.
11. A machine of the class described comprising in combination a bag magazine, means for successively withdrawing bags lengthwise from

the bottom of the magazine, a receiving table or bed, forwarding rollers for receiving the withdrawn bags and depositing them upon said table or bed, a pusher for pushing the bags laterally from said table, cams controlling said grippers, driving mechanism for said cams, rollers and pusher, and means for adjusting said grippers, rollers, cams and driving mechanism relatively to the bag magazine to accommodate the machine to different length bags.

10

ADOLPH POTDEVIN.
